UNITED STATES PATENT OFFICE.

JONAS NORTHRUP, OF HOPEDALE, MASSACHUSETTS, ASSIGNOR TO
DRAPER COMPANY, OF HOPEDALE, MASSACHUSETTS, A CORPO-
RATION OF MAINE.

SELF-THREADING LOOM-SHUTTLE.

No. 823,626.

Specification of Letters Patent.

Patented June 19, 1906.

Application filed July 12, 1905. Serial No. 269,328. (Model.)

To all whom it may concern:

Be it known that I, JONAS NORTHRUP, a citizen of the United States, residing at Hopedale, county of Worcester, and State of Massachusetts, have invented an Improvement in Self-Threading Loom-Shuttles, of which the following description, in connection with the accompanying drawings, is a specification, like characters on the drawings representing like parts.

This invention relates to loom-shuttles; and it has for its object the production of simple and efficient means for preventing or reducing to a minimum the wear on certain parts of the shuttle due to the friction of the yarn passing thereover.

In hand-threaded shuttles, or those in which a delivery-eye having a continuous periphery is used, it has been customary to insert a collar, short tube, or eyelet in the shuttle-eye made of some hard and smooth wear-resisting material, such as porcelain or similar material.

"Self-threading shuttles," technically so termed, have an open delivery-eye—*i. e.*, in which the periphery of the eye is intersected by a slot or passage through which the thread is drawn and directed into the eye—and in automatically-self-threading shuttles a metal threading device is provided, which automatically assumes control of the thread and then directs it through the entrance-slot to the delivery-eye. Shuttles of this latter type are used in looms wherein the running shuttle is automatically provided with fresh filling when necessary, and in actual practice such shuttles have been provided with steel pins, one at each side of the delivery-eye, to resist wear and transfer it from the wood forming the eye, and the threading device has also been provided with a steel guide pin or prong around which the thread draws when its direction is changed to pass through the delivery-eye. When using such shuttles with certain kinds of yarn, more especially woolen or worsted yarn, it has been found that the eye-pins and the guide pin or prong referred to wear very rapidly, so rapidly that in a short time they become so cut and scored as to render the shuttle useless.

In accordance with my present invention I have devised simple, novel, and efficient means for obviating the objections above set

forth, having more particular reference to automatic self-threading shuttles, which from their peculiar construction and mode of controlling the thread require a very unusual arrangement of the wear-resisting means. 55

The various novel features of my invention will be fully described in the subjoined specification and particularly pointed out in the following claims.

Figure 1 is a top plan view of the delivery end of an automatically-self-threading loom-shuttle with one embodiment of my invention applied thereto, a portion of the threading device being broken out to show the parts beneath it. Fig. 2 is a side elevation of the portion of the shuttle shown in Fig. 1. Fig. 3 is a cross-sectional view on the line 3 3, 65 Figs. 1 and 2, looking toward the right to show more clearly the wear-resisting means. Fig. 4 is a perspective detail, and Fig. 5 a top plan view, of the wear-resisting means detached; and Fig. 6 is a longitudinal sectional view on the line 6 6, Fig. 1. 70 75

I have for convenience herein shown my invention as applied to a shuttle provided with a threading device illustrated in my United States Patent No. 769,914, dated September 13, 1904, though it will be understood that the specific structure of the threading device is not essential, as other forms may be used in connection with my present invention. The shuttle-body A, having an opening to receive the filling-carrier or bobbin B, Fig. 1, the side delivery-eye a, Fig. 2, having an entrance slot or passage a^x, and the metallic threading device or block, having the tubular thread-passage 4, the inlet 5, elongated 80 guard 8, thread-entrance 9, horn 12, head 13, having a beak 14, and the shield 15, overlapping the beak, may be and are all substantially as in said patent and operate as therein set forth. In my present invention, however, I omit entirely the wear-pins at the sides of the delivery-eye and also the usual steel guide-prong depending below the horn, and, as shown in Figs. 3 and 6, I form a downwardly - open pocket or socket 20 in the 85 90 95 threading-block back of the horn for a purpose to be described.

The shuttle-wood is cut out behind the delivery-eye and at the front of the threading-block to receive the wear-resisting means embodying my present invention, the same be- 100 105

ing herein shown as a base portion 30, having at one side two upturned abutments 31 32, the space between them being shaped to present an eye 33 and a slot-like entrance thereto 34.

5 An upright guide-prong 35 is formed on the base, so located that when the base is in proper position the upper end or tip of the prong will enter the pocket 20 in the threading device. (See Figs. 3 and 6.) The base, abutments, and prong are made integral and preferably of molded and hard-baked porcelain or similar material having a smooth, glazed, and very hard surface vitreous in 15 character, the porcelain being possessed of sufficient toughness to withstand the blows to which the shuttle is subjected. I do not confine my invention to porcelain, however, as any other material possessing the requisite 20 characteristics may be employed, such as glass or any vitreous-like material. The base 30 is seated in the recessed part of the shuttle-body in front of the threading device (see Fig. 6) and suitably secured in place, as 25 by cement, though an additional fastening may be provided, if desired, by means of a pin driven through the hole 36 in the base. The prong 35 serves to guide the thread as it turns from the passage 4 substantially at 30 right angles to pass through the delivery-eye and takes the place of the commonly-used steel prong depending from the threading device, and as the upper end of the guide-prong is housed in the pocket 20 the thread 35 cannot draw up over the prong or become caught as it is drawn along. This guide-prong is subjected to almost continuous rubbing friction by the thread, and as it is made of non-metallic and vitreous-like material 40 with a highly-polished smooth surface the friction is reduced to a minimum and no scoring or roughening of said prong can be effected.

The abutments 31 32 fit into the recessed 45 portion of the shuttle-body behind the part in which the delivery-eye a is formed, the eye 33 being smaller than but practically concentric with the eye a , as shown in Fig. 2, and the slots 34 and a^x practically register. As 50 the bearing-faces of the abutments are rounded, as shown, and are hard and smooth, the wear of the thread as it passes through the side of the shuttle is minimized and made of practically no effect, owing to the 55 character of the material of which said abutments are made.

The threading device operates in usual manner and is not interfered with in the least by the wear-resisting means hereinbefore described. Said means can be made easily and cheaply. It will under ordinary circumstances last as long as the shuttle, and if it should become broken the block can be removed and a new one inserted with very 65 slight effort. The thread is kept down in

proper position partly by the shape of the eye 33 and partly by the overhanging edge 21 at the bottom of the pocket 20, extended rearwardly from the heel 22 of the horn 12, as best shown in Fig. 6.

70

Various changes in the shape of the wear-resisting means may be made to conform to the shape of the shuttle and adjacent portions of the threading device without departing from the spirit and scope of my invention.

75

Having fully described my invention, what I claim as new, and desire to secure by Letters Patent, is—

1. In a loom-shuttle having a side delivery-eye and an open slot leading thereto, means to direct the thread through the slot and into the delivery-eye, and a separate non-metallic wear-resisting block inserted in the shuttle-body and having a slotted eye portion adjacent and registering with the delivery-eye and the slot leading thereto, to protect the shuttle-wood from wear by the passage of the thread.

80

2. In a loom-shuttle having an open delivery-eye for the thread, means to direct the thread into the eye to be delivered, and a separate eye-guard of vitreous-like material inserted in the shuttle-body and having an upturned thread-delivering portion adjacent and 95 registering with the delivery-eye of the shuttle at its inner side, to protect the contiguous shuttle-wood from wear by the thread.

90

3. The combination, in a loom-shuttle having an open, side delivery-eye, and means to automatically assume control of the thread and direct the same to the delivery-eye, to be delivered, of a separate porcelain block inserted in the shuttle-body and having an eye portion and a slot-like entrance thereto, said 100 eye portion and entrance being located adjacent the delivery-eye of the shuttle and registering therewith to sustain the thread as it is delivered and thereby protect the shuttle delivery-eye from becoming worn.

100

4. The combination, in a loom-shuttle having an automatic self-threading device and a side delivery-eye through which the thread draws, the shuttle-body being recessed behind and adjacent said delivery-eye, of a 115 separate hard, smooth-surfaced and non-metallic wear-resisting member having a slotted eye portion inserted in the said recessed portion of the shuttle-body, to register with and protect the delivery-eye and its entrance 120 and protect the same from wear, and an upturned guide on said member and around which the thread travels as it is drawn off to be delivered.

110

5. In a loom-shuttle having an open side 125 delivery-eye and recessed adjacent the same, a wear-resisting member of vitreous-like material inserted in the recess and comprising a supporting-base, an upturned eye portion thereon adapted to substantially line the de- 130

livery-eye and protect it from wear by the thread, an upright guide-prong on the base to change the direction of the thread as it passes laterally to the delivery-eye and separate means to prevent the thread from passing over said prong.

6. In a loom-shuttle having an open side delivery-eye and recessed adjacent the same, a wear-resisting member of glazed porcelain inserted in the recess and comprising a flat base having an upturned slotted eye portion adapted to substantially register with the delivery-eye and protect the same from wear by the thread, a guide-prong on the base adjacent the eye portion, to change the direction of the thread, and means to hood the tip of the prong.

7. In a loom-shuttle having an open side delivery-eye, an automatic self-threading device to direct the thread into the delivery-eye, said device having a depending horn to direct the thread to the eye in the threading operation and provided with a pocket, combined with a porcelain guard inserted in the shuttle-body and having an upturned, slotted eye portion adjacent and registering with the delivery-eye of the shuttle and prevent wear upon said delivery-eye, and a guide-prong on the guard upturned adjacent the base of the horn, to receive the thread therefrom and effect a change in the path thereof to direct it to the delivery-eye, the tip of the prong projecting into the pocket.

8. In a loom-shuttle having a side delivery-eye with a slot-like entrance thereto, and means to assume control of the thread and direct it automatically through said entrance and into the delivery-eye, the combination with a separate porcelain guard comprising a base, and an upright portion thereon having an eye and a slotted entrance therefor, located adjacent and registering with the delivery-eye and its slot-like entrance, to protect the same from wear by the thread as it is delivered, the thread drawing over the top of the base of the guard.

9. In an automatically - self - threading loom-shuttle having a slotted side delivery-eye, a threading device having a horn and a downwardly-open pocket behind it, and a porcelain wear-resisting block inserted in the shuttle and having upright abutments to present an eye and a slot registering with the slotted delivery-eye, and an upturned prong on said block adjacent the abutments and projecting into the pocket, the thread drawing around the prong as it passes laterally between the abutments and out through the shuttle-eye.

In testimony whereof I have signed my name to this specification in the presence of two subscribing witnesses.

JONAS NORTHRUP.
